UNITED STATES PATENT OFFICE.

GABRIEL KURTZ, OF MILWAUKEE, WISCONSIN, ASSIGNOR TO JOSEPH H. RICE AND IGNATUS FRIEDMANN, OF SAME PLACE.

OVERALLS.

SPECIFICATION forming part of Letters Patent No. 244,756, dated July 26, 1881.

Application filed January 22, 1881. (Model.)

To all whom it may concern:

Be it known that I, GABRIEL KURTZ, a citizen of the United States, residing at the city and county of Milwaukee, State of Wisconsin, have invented a new and useful Improvement 5 in Overalls, Pantaloons, and Drawers, of which the following is a full, clear, and exact description, reference being had to the accompanying drawings.

10 Figure 1 is a view of the overalls, pantaloons, or drawers, with the front open and turned back on one side, so as to show the inner side of one part of the front and the outside or face of the other part, and having the overalls, pantaloons, or drawers ripped and spread out so as to show the position of the strip B and the parts C C before the same are completed. Fig. 2 is a view of the ordinary strip or fly D which contains the button-holes. Fig. 3 is a 15 view of the overalls, pantaloons, or drawers having the parts C C turned or folded in their proper position, so as to cover and overlap the strip B. Fig. 4 is a sectional view of the overalls through the line X, as shown in Fig. 3, this sectional view showing the relative positions of the parts C C, D, and B, the broken line showing where the position of the parts C C are, and the broken and dotted lines showing the position of the strip B.

20 A represents the overalls, pantaloons, and drawers; E, the waistband.

The object of my invention is to prevent 25 overalls, pantaloons, or drawers from being torn from the waistband, and to prevent the seam in the crotch at the bottom of the opening in front from being torn or ripped apart.

B is a continuous strip of cloth placed on the inner side of the overalls, pantaloons, or drawers, and is firmly sewed to the waistband, and 30 extends down each side of the opening in front and across the seam at the bottom of the opening in front. The strip B is about one-half of an inch shorter than twice the length of the opening in front, and, each end being sewed to the band E, it does not quite reach the seam in 35 the crotch at the bottom of the opening in front,

and is sewed or attached to the band alone. After the strip B is secured, as described, the parts C C are turned or folded in and sewed to the overalls, pantaloons, or drawers, so as to 50 completely cover and overlap the strip B, as is shown in Fig. 4. The strip B, although sewed to the band alone and not being attached or sewed to the overalls, pantaloons, or drawers at any other place, is kept in its proper 55 position by the overlapping parts C C, which thus keep the strip B out of the way and prevent it from getting entangled with anything while the overalls, pantaloons, or drawers are being used or taken off or put on. The strip 60 B being sewed to the waistband E alone, all the strain that the strip B sustains falls upon the waistband E, and thus prevents any such strain from tearing the overalls, pantaloons, or drawers from the waistband E; and the 65 strip B being a little short, and not quite reaching the seam in the crotch at the bottom of the opening in front, it will receive and take up all the strain and pull that is apt to occur in putting on or taking off the overalls, pantaloons, 70 or drawers before such strain or pull can reach the seam at that point where the seam in the crotch meets the bottom of the opening in front.

Having thus described my invention, what I claim as new, and desire to secure by Letters 75 Patent, is—

As a new article of manufacture, overalls, pantaloons, or drawers having a strip, B, each end of which is securely sewed to the waistband E, and attached to the overalls, pantaloons, or drawers at no other point, said strip 80 extending from the band E down each side of the opening in front, so as to nearly reach the seam in the crotch at the bottom of the opening in front, and being covered and kept in 85 place by the overlapping of the parts C C, the same being constructed substantially as herein shown and described.

GABRIEL KURTZ.

In presence of—

JOHN NEWBAUER,
WM. RADUE.
